UNITED STATES PATENT OFFICE.

GEORGE H. PALLADY, OF ALLERTON, IOWA.

LOADING ATTACHMENT TO BINDERS.

1,154,542.

Specification of Letters Patent. Patented Sept. 21, 1915.

Application filed October 19, 1914. Serial No. 867,390.

To all whom it may concern:

Be it known that I, GEORGE H. PALLADY, citizen of the United States, residing at Allerton, in the county of Wayne and State of Iowa, have invented certain new and useful Improvements in Loading Attachments to Binders; and I do declare the following to be a full, clear, and exact description of the invention, such as will enable others skilled in the art to which it appertains to make and use the same.

The invention relates to an improvement in attachments to binders and the object of the invention is to provide a light, inexpensive and durable attachment to the binder which will receive the sheaves delivered over the deck by the discharge arms and deposit them on a wagon or other receiving vehicle accompanying the binder and located on the deck side thereof but some distance from the same, the arrangement effecting a quick and direct loading of the sheaves.

With the above object in view the invention consists essentially in the arrangement and construction of parts hereinafter more particularly described and later pointed out in the appended claims.

Figure 1 represents a plan view of my attachment as applied on a binder, the view also showing a portion of a traction engine and a wagon. Fig. 2 represents a rear view of the attachment and the binder and a portion of the accompanying wagon. Fig. 3 represents a detail side view of a portion of the binder deck and the attachment with the fingers in the normal or inactive position. Fig. 4 represents an enlarged detail perspective view of the joint formed between the forks and the fingers.

In the drawings like characters of reference indicate corresponding parts in each figure.

1 represents a binder of which 2 is the frame, 3 the bull wheel, 4 the deck, 5 the binder attachment presenting the discharge arms 6, 7 the tongue and 8 the shield, all these parts being of ordinary construction and as customarily found in machines of this class.

9 represents my loading attachment which is connected to the binder frame on the deck side and is now described in detail.

10, 11, 12, 13, 14 and 15 represent a series of similar slightly curved parallel arms having their inner ends permanently secured by

suitable rivets or bolts 15' to the under side of the deck and resting approximately midway of their length on a supporting bar 16 carried by a pair of braces 17 and 18 extending outwardly from suitable hangers or brackets 19 fastened to the binder frame.

The inner ends of the arms are slidably mounted on a channel iron bar 20 in turn carried by an angle iron 21, the angle iron being carried by end posts 22 which are at present part of the binder structure.

It is here explained that in binders the decks are shiftable and for this reason it is necessary to have the arms slidably mounted on the bar 20 and the bar 16 as the arms shift with the deck. The rear arm 10 is bent upwardly slightly more than the rest as it forms a guide for the heads of the sheaves passed over the attachment.

23 are equal length fingers jointed to the outer ends of the arms 11, 12, 13, 14, and 15. The joints between the arms and fingers are formed so that the fingers cannot buckle down but are free to turn upwardly under the action of the springs 24 located at the joints. (See Fig. 4.) The fingers are all connected by a coupling rod or wire 25 so that they operate together.

26 is a substantially U-shaped pressure rod having its ends connected to the outer ends of the shield 8, the body of the rod extending outwardly over the arms but parallel with the same and being suspended by a tie rod 27 connected to the binder attachment 5. The pressure rod is arranged in respect to the arms such that the sheaves passed over the deck and discharged by the discharge arms are forced outwardly over the arms being held on the arms in passage by the pressure rod. As each succeeding sheaf is passed over the deck it forces an advancing sheaf over the fingers, which fingers assume, owing to the action of the springs, an upright position immediately after the sheaf is finally discharged.

In order to understand the advantage of the attachment it is explained that where it is used a wagon or other such vehicle 28 accompanies the binder, the wagon being attached to a draft beam 29 secured to the back end of a traction engine represented at 30, the traction engine being utilized also to pull the binder. With this arrangement the sheaves are deposited directly onto the wagon which when fully loaded can be dumped in any convenient way.

Although it forms no part of this invention I prefer that the wagon be unloaded, by dumping, that is by dropping the rear end and elevating the forward end. It is with a wagon of this kind that the advantage of the pivoted spring pressed fingers is apparent. They allow the sheaves to be delivered well onto the wagon but each time a sheaf is deposited on the wagon they spring up so that they are entirely clear of the wagon side. Accordingly the fingers are always clear of the wagon when it is to be dumped and will in no way interfere with its operation.

I do not wish to be restricted in any way to the precise manner in which the arms are attached to the deck or to the manner in which they are supported slidably on an under structure as various ways of accomplishing this could be readily suggested without the least departing from the spirit of the invention. Neither do I wish to be limited to the precise form of spring joint shown between the fingers and the forks, as various other mechanical arrangements could be readily suggested which would operate to equal effect.

The principal feature of the invention resides not in the details of the construction but in the provision of an attachment which forms in reality an extension of the deck whereby sheaves delivered from the deck can be deposited on an accompanying vehicle located at some distance from the deck.

What I claim as my invention is:

1. The combination with the deck of a binder, of a supplemental deck secured to and extending laterally from the aforesaid deck, and a fixed supporting bar carried by the binder frame upon which the supplemental deck rests slidably.

2. The combination with the deck of a

binder, of a series of outstanding arms secured thereto and extending laterally therefrom, and a fixed horizontally disposed supporting bar carried by the binder frame upon which said arms rest in slidable relation. 45

3. The combination with the deck of a binder, of a supplemental deck secured to 50 and extending laterally from the aforesaid deck, a fixed supporting bar carried by the binder frame upon which said supplemental deck rests slidably, and a pressure rod overlying the supplemental deck to retain the 55 same in contact with the supporting bar when the machine is in operation.

4. The combination with the deck of a binder and the shield thereover, of a series of outstanding arms extending laterally 60 from said deck and secured thereto at their inner ends, a series of upright spring pressed fingers located at the outer ends of the arms, a pressure rod overhanging the arms, and means carried by the binder frame upon 65 which said arms rest in slidable relation.

5. The combination with the deck of a binder, of an inner supplemental deck section secured to and projecting laterally from the aforesaid deck, an outer laterally swinging supplemental deck section hinged to and rising from the outer end of the inner section, spring means normally retaining the outer section in substantially upright position, and stop means carried by one of said sections to limit the outward movement of the outer laterally swinging section. 70 75

In testimony whereof I have hereunto set my hand in presence of two subscribing witnesses.

GEORGE H. PALLADY.
